UNITED STATES PATENT OFFICE

BURTON J. NEILL, OF OAKLAND, CALIFORNIA

GRAND PIANO ACTION

Application filed March 9, 1928, Serial No. 260,424. Renewed May 4, 1932.

This invention relates to improvements in grand piano actions and has particular reference to an action which is capable of repeating in counter-distinction to many grand piano actions wherein the full action of the key must take place before the key can be again struck.

Another object of the present invention is to provide means whereby the action may be accommodated in the same space now employed for this purpose.

Another object is to provide a device of this character which is simple in construction and assembly, and one which is easy to regulate.

A further object is to produce an action which is economical to manufacture.

A still further object is to provide an action wherein the absence of any rubbing parts results in lightness of touch without the employment of counter-balance weights thereby securing a quicker and more certain repetition under any dip of the key.

Other objects and advantages will be apparent during the course of the following description.

In the accompanying drawing forming a part of this specification, and in which like numerals are employed to designate like parts throughout the same,

Figure 1 is a fragmentary side elevation, partly in section and illustrates my improved grand piano action in its entirety.

Figure 2 is a sectional view taken approximately on line 2—2 of Figure 1, looking in the direction of the arrows.

In the accompanying drawing wherein for the purpose of illustration is shown a preferred embodiment of my invention the numeral 5 designates the key of a piano which is fulcrumed on the pin 6 and carries an upstanding diagonal rod 7 at its rear end upon which is positioned a check 8 carrying a pad 9 which is retained by a leather strip 11.

At 12, I have shown a rail which serves to

secure a support 13 to which the wippen 14 is pivoted as at 16. This wippen carries a downwardly extending portion 17 upon which a pad 18 is secured. This pad is adapted to contact an adjusting screw 19 carried upon the key 5.

Pivoted as at 21 is a jack 22, the upper end of which normally lies beneath the roller 23 carried upon the hammer shank 24. This hammer shank is pivoted as at 26 to the hammer butt 27 carried upon the action-rail 28. The hammer shank carries a head 29 having the customary nose 31 upon which the felt hammer head 32 is secured. This hammer head 29 has a downwardly extending tail 33 which is adapted to be engaged by the check 8 in a manner which will be later described.

A counter-balance spring is shown at 34, and has one end secured as at 36 in a shallow conical cavity arranged in the underside of the hammer shank 24, while its opposite end is disposed in a socket formed in one end of an adjusting screw 37 which is threaded in the upper end of the support 13, the adjusting screw having a flat opposite end to provide a finger hold, whereby the screw can be rotated as will be apparent.

Coils 38, 39, 41 and 42 are formed throughout the length of the spring in order to increase its resiliency and also in order to change its direction of travel. The coil 39 is so formed as to encircle a pivot pin 43 carried in the upstanding brace 44 mounted upon the wippen 14. The jack 22 carries a trip 46 which is adapted to engage the under-side of the jack regulating button 47. A jack stop is shown at 48 and is carried upon the wippen 14. This stop is engaged by the ordinary jack button 49.

A bridle tape is secured to one side of the jack as shown at 51 and has its opposite end connected to the hammer shank as shown at 52. This bridle tape is broken away in Figure 1 in order to better illustrate my invention.

The purpose of the bridle tape is to keep the top end of the jack and the hammer roller in close relation to each other. The tendency of the repeating spring is to hold the hammer up after the stroke or retard its downward movement, and without the bridle strap the jack and wippen would fall back faster than the hammer, impairing the repetition in rapid action and would cause an audible knocking of the jack against the hammer roller in repeated strokes. In other words, the weight of the wippen and jack attached to the hammer shank by the bridle strap, overcomes the extreme tension of the spring and brings the movable parts down as a unit.

15 The operation of my device is as follows:—

When the key 5 is struck upward movement is transmitted through the adjusting screw 19 to the wippen 14, the jack moving upwardly pushes upon the roller 23 thus lifting the hammer shank and hammer so that the same will strike a blow upon the string of the instrument upon which the action is positioned. As the counter-balance spring 34 is under tension at all times, it tends to relieve the weight of the hammer and as the hammer lifts the end of the spring travels with it, with increasing tension, due to the fact that the wippen in raising, moves the pivot pin 43 upwardly and backwardly thereby changing the fulcrum point of the spring with relation to the adjusting screw 37 which remains stationary and as the connection of the spring 34 with the screw 37 is mounted above the axis of the wippen 14, compression action on the spring results between the screw 37 and pin 43 which increases the upward angular movement of the portion of the spring which bears upon the hammer shank 24.

When the wippen has reached the dotted line position the trip 46 has engaged the jack regulating button with the result the jack 22 will be moved out from under the roller, thereby permitting the hammer to drop back away from the string. The hammer however, cannot drop back the full distance due to the fact that the check 8 has been moved to the dotted line position shown in Figure 1 and therefore the tail 33 of the hammer head will come into engagement with the strap 11 on the check and be held thereby until the key is entirely released. In this position the jack will be closer to the hammer shank and therefore at one side of the roller, thereby causing the bridle tape to slacken and release its pull upon the hammer shank. As pressure upon the key is released, the parts tend to return to their normal position, but the spring 34 will support the hammer in its suspended position until the jack 22 has returned under the roller 23 which will take up the slack in the bridle tape. At this point the tendency of the spring is to hold the hammer in the suspended position and the added

weight of the jack and wippen which are connected to the hammer by the tape overcomes the resistance of the spring and pulls the hammer down quickly.

As soon as the jack is under the roller the 70 action is ready for the next stroke, no matter in what position the hammer may be. In other words, the action in moving the jack beneath the roller is so quick that it is possible to strike the key before the same has 75 entirely returned to its normal rest position.

It is to be understood that the form of my invention herewith shown and described is to be taken as a preferred example of the same, and that various changes relative to 80 the shape, size, material and arrangement of parts may be resorted to without departing from the spirit of the invention, or the scope of the subjoined claims.

Having thus described my invention, I 85 claim:—

1. In a piano action, a key fulcrumed intermediate its ends, a wippen pivotally supported above said key, a hammer including a shank pivotally secured above said wippen, a spring interposed between said wippen and said shank, said spring having one end secured in a cavity in said shank and bearing against the latter, means receiving the opposite end of said spring and mounted above the 95 axis of the wippen, means rising from said wippen and carrying said spring and said means cooperating with each other to increase the upward angular movement of the portion of the spring which bears upon the shank upon upward movement of the wippen.

2. In a piano action, a key fulcrumed intermediate its ends, a rail secured above said key, a support secured to and rising from said rail, a wippen having one end pivotally secured to said support and being associated with said key for movement from the latter, an upstanding brace carried by the wippen, a hammer including a shank pivotally secured above the wippen, an adjusting screw threadedly secured in the support and arranged above the axis of the wippen, a pivot pin carried by the upstanding brace, a spring coiled about the pivot pin intermediate its ends and having one end received in a socket formed 115 in the adjusting screw while its opposite end bears against the hammer shank and said spring being compressed between its connection with the pivot pin and its connection with the adjusting screw to increase the upward angular movement of the portion of the spring which bears upon the hammer shank when said key is struck.

3. In a piano action, a key fulcrumed intermediate its ends, a wippen movable upon movement of said key and having one end pivotally secured, a jack pivotally secured to the opposite end of said wippen, a hammer including a shank pivotally secured above said wippen, means secured to said shank and 130

engageable by the jack, a bridle tape secured to said jack and shank respectively, means rising from said wippen, a spring having connection intermediate its ends with the last
5 mentioned means and having one end bearing against the shank, said spring having its opposite end mounted above the axis of the wippen, and said spring being compressed between its intermediate connection and its end
10 mounted above the axis of the wippen to increase upward angular movement of the portion of the spring bearing upon the shank when the key is struck.

15 In testimony whereof I affix my signature.
